[22] Filed: Oct. 20, 1997

DESCRIPTION

[51] LOC (6) Cl. 06-01

FIG. 1 is a left side elevational view of a compact portable outdoor all-terrain seat showing my new design;
FIG. 2 is a right side elevational view thereof;
FIG. 3 is a rear elevational view thereof;
FIG. 4 is a front elevational view thereof;
FIG. 5 is a top plan view thereof; and,
FIG. 6 is a bottom plan view thereof.

[52] U.S. Cl. D6/368; D6/375

The fragmented cross-hatching shown on the seat and the straps is understood to represent fabric and would be continuous throughout the implied areas.
